FAN HOUSING

John Maynard Morrison, Carss Park, near Sydney, New South Wales, Australia, assignor to Centriflo Pty. Limited, New South Wales, Australia

Filed Dec. 13, 1961, Ser. No. 67,899

Term of patent 14 years

Claims priority, application Australia Aug. 3, 1961

(CL. D62—4)

FIG. 1.

FIG. 2.

FIG. 3.

FIGURE 1 is a bottom perspective view of a fan housing showing my new design.

FIGURE 2 is a front elevation thereof.

FIGURE 3 is a side elevational view of the housing. The back is conventionally plain.

The end opposite that shown in FIG. 1 is substantially the same in appearance as that shown.

I claim:

The design for a fan housing, as shown and described.
